ROLL PAPER CUTTER

Filed March 22, 1928

FIG. 3.

FIG. 4.

INVENTOR,
JAMES W. MCCLINTOCK.
By Martin P. Smith, Atty.

UNITED STATES PATENT OFFICE

JAMES W. MCCLINTOCK, OF LOS ANGELES, CALIFORNIA, ASSIGNOR TO E-Z REACH PAPER CUTTER CORPORATION, LTD., OF LOS ANGELES, CALIFORNIA, A CORPORATION OF CALIFORNIA

ROLL-PAPER CUTTER

Application filed March 22, 1928. Serial No. 263,637.

My invention relates to a roll paper cutter and has for its principal object, the provision of a relatively simple, inexpensive and convenient device that is capable of being readily combined with a roll of wrapping paper for supporting the web of paper as it is unwound from the roll, and said device being provided with a straight edge along which the web of paper may be torn.

10 A further object of my invention is to provide a roll paper cutter with a roller over which the web of paper passes as it is unwound from the roll, said roller having combined therewith friction devices that are instrumental in preventing the paper from unwinding too freely, and said friction devices being formed so as to deflect the end of the web of paper downwardly away from the tearing edge where said free end may be readily grasped to permit a portion of the web to be unwound from the roll, and torn off by engagement with the edge of the cutter. A further object of my invention is to provide a roll paper cutter that may be conveniently

25 combined with a holder and a roll of paper, or said cutter may be located on a suitable support above or in front of a roll of paper, and which latter may be mounted at any convenient point, for instance, beneath a counter or on the top, side or end of a counter, showcase or the like.

With the foregoing and other objects in view, my invention consists in certain novel features of construction and arrangement of parts that will hereinafter be more fully described and claimed and illustrated in the accompanying drawing, in which—

30 Fig. 1 is a perspective view of a roll paper cutter constructed in accordance with my invention.

Fig. 2 is an enlarged cross section taken on the line 2—2 of Fig. 1.

Fig. 3 is an end elevational view of the cutter.

45 Fig. 4 is a top plan view of the end portion of the cutter.

Referring by numerals to the accompanying drawings which illustrate a practical embodiment of my invention, 10 designates a plate preferably constructed of sheet metal

and the front portion of said plate is curved downward to a slight degree and the edge 11 of said downwardly curved portion constitutes a tearing edge against which the web of paper is engaged and torn.

55 Projecting rearwardly from the end portions of plate 10, are short integral arms 12 that occupy the same horizontal plane with the body of the plate 10, and depending from the inner edges of these arms 12, are flanges 13 that occupy substantially vertical positions.

Formed integral with and projecting upwardly from the outer portions of the arms 12, are flanges 14, the forward portions thereof 60 of extending forwardly with respect to the rear edge of the plate 10, and formed integral with the rear ends of the upturned flanges 14 and the rear ends of the arms 12, are ears 65 or plates 15 that are perforated for the reception of screws or like fastening devices that are utilized in attaching the cutter to a suitable support.

70 Formed in the intermediate portions of the arms 12 and the depending flanges 13, are short slots 16, and occupying the lower portions of these slots are trunnions 17 that project from the ends of a small roller 18, and which latter occupies a position immediately to the rear and parallel with plate 10.

75 Arranged beneath the plate 10 and the forward portions of combined paper tensioning and deflecting members 19, and the forward ends of these members are rigidly secured to the forward portion of plate 10, in any suitable manner, either by being spot welded, or by means of rivets or like fastening devices.

80 The rear portions 20 of these combined tensioning and deflecting members 19 are curved so that they fit directly over the upper portion 85 of the roller 18, and the intermediate portions of said members, or those portions directly in front of the roller are bent so as to form depending curved portions 21.

85 These tensioning members are preferably formed of resilient metal and they are mounted so that their curved rear ends 20 bear with a certain degree of friction, upon that portion of the web of paper *p* that passes over the roller 18.

When my improved paper cutter is positioned for use, it is fixed to a suitable support, preferably above or above and in front of a roll of paper and the web of the paper passes from the roll upwardly or forwardly over the roller 18 and beneath the rear portions 20 of the tensioning members.

The pressure of the portions 20 of the resilient tensioning members on that portion of the paper that passes over roller 18 firmly holds the paper on the roller and due to the provision of the depending intermediate portions 20 of the tensioning device, the free end of the web of paper projects downwardly in front of the roller 18 so that it occupies a position beneath the rear portion of plate 10.

When a portion of the roll of paper is to be unrolled and torn off, the depending end of the web of paper beneath the plate 10 is engaged between the thumb and fingers and drawn downwardly and outwardly, until the desired amount of paper has been unrolled, and the web of paper is now drawn upwardly and laterally so as to bear against the front edge 11 of the plate 10, and thus, that portion of the paper beyond or in front of the cutter will be torn off by engagement with the front edge 11 of said plate 10.

As the unwound portion of the paper is thus torn off, the free end of the web or that portion beneath plate 10, will swing downwardly, away from the plate 10 to a position immediately in front of and below the roller 18, which action is brought about the depending intermediate portions 20 of the tensioning device, which depending portions function as deflectors, and thus the end of the web of paper occupies a position where it may be conveniently grasped when another portion of paper is to be unwound and torn off.

A roll paper cutter of my improved construction may be conveniently combined with the ordinary or standard forms of roll paper holders, or said cutters may be attached to any convenient support above or in front of a roll of paper that is mounted for rotation in suitable supports or bearings.

Thus, it will be seen that I have provided a roll paper cutter that is relatively simple in construction, inexpensive of manufacture, and which is very effective in performing the functions for which it is intended.

It will be understood that minor changes in the size, form and construction of the various parts of my improved roll paper cutter may be made and substituted for those herein shown and described without departing from the spirit of my invention, the scope of which is set forth in the appended claims.

I claim as my invention:

1. A roll paper cutter comprising a plate having a tearing edge, arms formed integral with and projecting rearwardly from the ends of said plate vertically disposed slots formed in the intermediate portions of said

arms, a roller having its ends journaled in said slots and a plurality of resilient paper tensioning and deflecting members having their forward portions secured to the underside of said plate and extending rearwardly over said roller.

2. A roll paper cutter comprising a plate having a tearing edge, arms formed integral with and projecting rearwardly from the ends of the said plate which arms are substantially Z-shape in cross section with slots formed in the intermediate portions of said arms, a roller having its ends journaled in said slots, a plurality of combined paper tensioning and deflecting members having their forward portions secured to the underside of said plate and extending rearwardly over said roller, and the intermediate portions of which members are curved downwardly to form paper deflectors.

In testimony whereof I affix my signature.

JAMES W. McCLINTOCK.
